E. BROOKINS

CUT-OUT FOR MUFFLERS OF EXPLOSIVE ENGINES

Filed May 25, 1922

UNITED STATES PATENT OFFICE.

EARL BROOKINS, OF GLENDALE, CALIFORNIA.

CUT-OUT FOR MUFFLERS OF EXPLOSIVE ENGINES.

Application filed May 25, 1922. Serial No. 563,696.

To all whom it may concern:

Be it known that I, EARL BROOKINS, a citizen of the United States, residing at Glendale, in the county of Los Angeles and State of California, have invented a new and useful Improvement in Cut-Outs for Mufflers of Explosive Engines, of which the following is a specification.

My invention relates to what is familiarly known as cut-outs adapted to be arranged in the exhaust pipe of a gas engine to discharge the burnt gases or exhaust before entering the muffler.

The object of the invention is to provide an efficient device of this character having the structural characteristics hereinafter more fully described. To this end the device is of a form that is easily manipulated, and has a capacity for use on different gas engine installations as they are employed on the different types of automobiles. A further object of the invention is to provide a cut-out in which the spring that controls the flap or valve is so located as to avoid heat interfering with the efficiency or life thereof, all as will hereinafter more fully appear from the description to follow and in connection with the accompanying drawings.

Referring to the said drawings in general terms, Fig. 1, is a side elevation of the exhaust pipe and muffler, and the cut-out in its relative position. Fig. 2 is a bottom plan view of the cut-out, the exhaust pipe being broken off at each end thereof. Fig. 3 is a longitudinal mid-sectional view of the device, and Fig. 4 is a cross sectional view.

In a more particular description of the invention, the same reference characters indicate the same parts in the drawings.

The housing or body is formed of sheet metal in two parts, upper and lower; these parts are designated by —1— and —2— each having flanges —3— and —4— extending the length thereof, and firmly united to inclose the exhaust pipe —5—. Screws —6— pass through openings in the said flanges and the two parts comprising the housing are made tight around said pipe by nuts —7—.

The position of the device is such as to intercept the exhaust gases coming from the engine and before reaching the muffler —8— and to permit the escape thereof in volume through the opening —9— in the lower portion. The portion of the exhaust pipe enclosed by the device is cut out as at —10—.

The lower portion of the housing is extended down at the sides as shown in Fig. 4 to provide the opening —9— in the bottom thereof below the opening in the exhaust pipe and which is substantially the length of the opening in the exhaust pipe. The portion of the metal forming the margin —11— of said opening —9— is flat as shown in Fig. 2 to form a proper seating surface for the flap valve —12— which lies on the inside of the housing in the lower portion thereof and controls the discharge opening —9—. The metal of the lower part —2— of the housing is bulged downwardly and cross-wise to provide a seat portion —13— for a shaft —12'— which lies across the lower portion —2— of the housing and extends through openings in the sides of said lower portion, and whereby a suitable bearing for said shaft is provided. One end of the flap valve —12— is suitably attached to the shaft —12'— and as the said shaft turns the flap valve raises or lowers. The ends of the said shaft —12'— are extended a suitable distance beyond the side flanges —3— and —4— of the housing and either end may have a disk —14— fastened to it by means of which a suitable connection is formed with one or the other side of the device and the operating lever or treadle —16—. That is to say, in some makes of automobiles the connection or cable —16— between the cut-out and the operating treadle —16— should be on the right of the cut-out, while in others said connection should extend from the left thereof. The connection is made by means of a bent lever —17—, one end of which is flat or in the form of a disk —18— which fits against the perforated disk —14— made fast to one or the other end of the shaft —12'—. The position of the said lever —17— with reference to the shaft is susceptible of a substantial range of adjustment, for example, the said disk —14— has a number of openings —19— in it, any one of which may be employed to connect the disk —18— of the lever —17— and the position of the lever will be on an angle accordingly, thus rendering more accurate and positive the operation of the flap valve —12—.

The connection between the disks —14— and —18— is made by means of a screw —24—. When not moved to the open position through pressure on the treadle —16—, the said flap valve is maintained in the

closed position by the tension of a spring
—20—

As it is essential that the said spring be
5 protected from the heat due to the passing
of the exhaust product, and the life and effi-
ciency thereof be accordingly enhanced, the
10 said spring is mounted away from the cut-
out by means of an arm —21— extending
from the disk —14— and to which one end
10 of the spring is attached. A bent arm
—22— extends from one of the side flanges
—3— or —4— to which the other end of the
spring is attached. Owing to the disk
15 —14— being rigid on the shaft —12— it
will be readily seen that the tension of said
spring normally maintains the flap valve
—12— in the closed position.

The connection or cable —16'— may be
20 guided to the operating lever over suitable
pulleys —23— as may be required. The
ends 1' of the housing are contracted within
the circumference of the body in order to
snugly fit around the exhaust pipe.

Having described my invention and the
25 manner of its operation, I claim:

A cut-out for the control of the exhaust
products of gas engines, the same compris-

ing upper and lower portions united to form
a body surrounding the exhaust pipe, the
lower body portion being extended slightly
30 below the lower side of the exhaust pipe and
terminating in a bottom with an opening
therein which lies close to an opening in
said exhaust pipe, the opening in said bot-
35 tom being inclosed at the sides and one end
by a flat marginal portion which forms a
valve seat, and at the other end by a trans-
verse concave portion forming a shaft bear-
ing, and an arm extension on an end of the
40 said lower portion, a flap valve seating upon
the side and end margins of said opening
immediately below the opening in the ex-
haust pipe, a shaft to which said valve is
45 united at one end, said shaft having a bearing
in the said transverse concave portion
of said bottom, a perforated disk con-
nectible to either end of said shaft and hav-
ing an extension therefrom, a spring con-
50 nected to said extension and to the arm ex-
tension of the lower body portion, and an
operating lever having one end of disk form
connectible in different positions to the said
perforated disk.

EARL BROOKINS.
